(57) **CLAIM**

We claim the ornamental design for a rearview mirror for an over the highway truck, as shown and described.

DESCRIPTION

FIG. 1 is a perspective view of the rearview mirror for an over the highway truck of our new design;

FIG. 2 is a perspective view of the rearview mirror;

FIG. 3 is a top plan view of the rearview mirror;

FIG. 4 is a left side elevational view of the rearview mirror;

FIG. 5 is a front elevational view of the fairing trim piece;

FIG. 6 is a right side elevational view of the rearview mirror;

FIG. 7 is a rear elevational view of the rearview mirror; and,

FIG. 8 is a bottom plan view of the rearview mirror.

The broken lines shown are for illustrative purposes only and form no part of the claimed design.
